ELECTROLYTIC CELL.

1,073,559.

Specification of Letters Patent. Patented Sept. 16, 1913.

Application filed August 23, 1907. Serial No. 389,824.

To all whom it may concern:

Be it known that we, EDWARD A. ALLEN and HERBERT I. ALLEN, of Portland, in the county of Cumberland and State of Maine, have invented certain new and useful Improvements in Electrolytic Cells, of which the following is a specification.

This invention has relation to electrolytic cells of the Moore and Allen type, in which the cathode is unsubmerged and in which the electrolyte percolates from the anode chamber through a diaphragm into contact with the cathode. One of the greatest difficulties that has always been met with in the operation of electrolytic cells, is the back percolation of the catholyte into the anode chamber and the electrolysis of the hypochlorites formed leading to the destruction of the anodes. Another difficulty arises from the constant electrolytic action which goes on in the cell, for, as the electrolyte becomes impoverished of salt, the water is electrolyzed, giving off oxygen at the anode, and causing the destruction of the anodes.

The object of the present invention is to remedy these evils and this is accomplished in accordance with our invention by constructing the anode in such manner that there is a constant circulation of the electrolyte in the anode chamber; and secondly, in supplying salt to the anode chamber to be taken up as the electrolyte becomes impoverished, and thirdly, limiting the active surface of the cathode to the area of the diaphragm through which percolation takes place, so that the product of the electrolysis may be readily removed.

In addition thereto, the invention has further for its object to prevent the deterioration and destruction of the diaphragm by providing means for resisting the outward hydrostatic pressure of the electrolyte in the anode chamber. According to the illustrated embodiment of the invention, this is secured by providing braces which bear against the cathode on its outer surface and prevent it and the diaphragm from bending outward, without checking or retarding the electrolytic action or the discharge of the catholyte.

Referring to the accompanying drawings which illustrate one embodiment of the invention and to which it will be understood

the invention is not limited, Figure 1 represents an electrolytic cell which may be considered as the preferred form of the invention. Fig. 2 represents an end elevation of the same. Fig. 3 represents a vertical transverse section through the cell. Fig. 4 represents a vertical longitudinal section through the cell. Fig. 5 represents the construction of the multiple anode. Fig. 6 represents the supports for the anode as being formed thereon.

Referring to said drawings, the cell body 65 is constructed with end walls 10 and side walls, or what we term free boards, 11, which connect the end walls at their upper portions. The end walls are secured to a bottom wall or plate 12, the walls 10, 11, 70 12, being all formed of slate or other suitable material, such as cement, which will withstand the electrolytic action. Secured to the side faces of the bottom plate 12 and the end walls and to the outer faces of the 75 free boards, or side bars 11, are the diaphragms 13 which are preferably formed of one or more layers of asbestos paper or other material which will permit comparatively free percolation of the electrolyte 80 which is contained within the cell. The diaphragms are secured in place by rectangular frames 14 which are preferably made of metal such as iron, there being between these frames and the margins of the dia- 85 phragms, gaskets 15 of rubber or other insulating material. The margins of the diaphragms also overlap gaskets 16 of insulating material which are secured to the edges of the end walls 13, the side bars 11, and the 90 bottom plate 12. The frames 14 are attached to the cell by clamps 17 which bear against flanges or strips 18 attached to the side bars and against flanges on the upper longitudinal bars of the frame, said clamps 95 being secured in place by screws 19. The lower longitudinal bars of the frames 14 are clamped to the base plate by U-shaped clamps 20 and screws 21 passed through the upturned ends thereof and engaging flanges 100 on the lower bars of said frames. In addition, we may employ similar clamps 22 which extend across the ends of the cell as shown in Fig. 2 with screws 23 engaging flanges on the upright bars of the frames 105 14. The construction thus far described,

provides an anode chamber for the reception of the anode and an electrolyte consisting of any saline solution which it is desired to electrolyze.

5 The cathode consists of several (two or more) layers of foraminous material such as wire gauze capable of maintaining in its pores or interstices a body of the catholyte. These cathodes are indicated at 24, and they 10 are placed with their inner faces against the outer faces of the diaphragms. The edges or margins of the cathodes are bent outwardly at right angles to their active faces, as clearly shown in Fig. 3, and these 15 outwardly projecting margins or edges are secured to the inner faces of the rectangular frames 14 by clamping bars 25 and screws 26. In accordance with this construction, the active faces of the cathodes are limited 20 to the exposed faces of the diaphragms so that there is no danger whatever of electrolysis going on except where the electrolyte percolates through the diaphragm, and hence no anions are liberated except at 25 points where they are carried off by the catholyte as the latter flows down through the cathode and on the face thereof.

In order that the caustic fumes may not escape into the room in which the cells are 30 installed, we attach to the outer edges of the frames 14, plates 27 which are clamped in place by small rectangular frames 28 and screws 29; and for the purpose of preventing the diaphragms and cathodes from yielding 35 outward under hydrostatic pressure of the solution contained in the anode chamber, we provide at various points braces 30. Each brace consists of a small rod which is bent substantially U-shaped with its ends attached 40 to the plate so that its middle portion bears against the cathode. Instead of having one brace extending the entire height of the cathode, we preferably employ two or more to gain additional strength.

45 It will be seen that on each side of the cell there is a rectangular frame to which is secured the cathode and the outer plate 27, so that the cathode chamber thus formed and the attached cathode may be removed as a 50 unit, so as to expose the diaphragm and permit its renewal or replacement. In practice, the hollow frame, the cathode, the brace rods 30 and the outer plate are all assembled and secured together, so that, when the diaphragm 55 has been stretched across the open side of the anode chamber, the assembled parts are clamped against the edges of the diaphragm. This constitutes one of the advantageous features of our cell.

60 The anode chamber is closed at the top by a cover 33 which is luted in place, there extending from the cover a conduit 34 for the gas which is given off in the anode chamber.

The anode is what we term a "multiple 65 anode," being so constructed as to permit of

the circulation of the electrolyte in the anode chamber. It consists of parallel bars 35 35 of carbon or graphite which are separated to leave a comparatively large open space between their confronting inner faces. At 70 their upper edges these bars are dove-tailed as at 36, to receive dove-tailed crossbars 37 which are likewise formed of carbon or graphite. These cross-bars serve to connect the parallel bars 35 and to hold them in 75 proper relation. Preferably, though not necessarily, the bars 35 are each longitudinally divided into sections indicated at *a* and *b*, which are separated by a passageway *c*. In this event, we employ additional 80 crossbars 38 which are oppositely dove-tailed to engage dove-tail grooves in the sections *a* and *b* of the side bars of the anodes. The exposed outer faces of the side bars of the anode may be substantially equal in area to 85 the faces of the diaphragms which are exposed to the electrolyte, although we preferably have the exposed area of the faces of the anode somewhat less than the exposed face of the diaphragm and the 90 active faces of the cathodes. The anode rests upon supports 39 which may take the form of glass bars of any suitable shape to elevate the anode above the bottom plate of the cell. These supports may however, be 95 formed of downward projections *X* on the plates as shown in Fig. 6.

The cross bars 37 38 of the anode have apertures 40 41 into which extend spindles or bars 42 which are formed of carbon or 100 graphite, and which extend upwardly through the cover 33 as illustrated in Fig. 4. Preferably these bars or spindles 42 are relatively large in cross section so as to reduce their resistance and enable us to use a current of relatively low voltage. The cover is provided with an upstanding flange 43 around the projecting portion of each bar or spindle in which is poured melted paraffin, tar or other material as at 44, which will 110 prevent the escape of gas from the anode chamber. At the top of each bar or spindle, there is a mercury cup 45 to receive the terminals of electric connectors which connect the anodes with the cathodes of an adjacent 115 cell or with the positive pole of a suitable electric generator. The anode of the next adjacent cell or the negative pole of the generator, is connected to mercury cups 46 which are electrically connected with the metallic frames 14, hereinbefore described, which are in electrical contact or connection with the cathodes, the latter being pressed thereagainst by the clamping bars 25.

In order that the electrolyte may be maintained at its highest point of saturation, we provide means for continuously supplying from the interior of the anode chamber, the salt of which the solution is made. This takes the form, in the present case, of 125

130

a basket or receptacle 50 which is made of hard rubber, earthenware, glass or any other material which will withstand the action of the chlorin liquor and gas, and it is provided with numerous perforations so that the electrolyte may pass through it. This receptacle or basket is placed between the side bars of the anode near the top thereof where the electrolyte is weakest, and it is supported by a tube 51 which depends from the cover 33. This tube may be made of the same material as that of which the basket or receptacle is formed, and it is provided at its upper end with an outwardly and downwardly extending flange 52 which dips into a lute 53 on the top of the cover 33. A removable cap 54 also extends into said lute so as to prevent the escape of gas from the cell into the atmosphere. The normal level of the electrolyte in the cell is indicated by the transverse dotted line α in Fig. 4, although this level will be raised as the diaphragm becomes more or less clogged so as to secure the same percolation of the electrolyte through the diaphragm, but in any event it is above the upper edges of the anode. The lower bent end of the tube 51, however, is below the level of the electrolyte in the anode chamber so that, when the cap 54 is removed for the purpose to be described, there is practically no escape of gas from the cell. In the receptacle is placed, as previously stated, a quantity of salt, to which fresh salt is added from time to time, so that there is always maintained in the basket or receptacle a quantity of salt which is accessible to the electrolyte in the anode chamber. Preferably, the salt which we employ is chemically pure to prevent the introduction of foreign matter into the cell.

The electrolyte is introduced into the cell in any usual or convenient manner through a conduit 55 into which the flow of the electrolyte is governed by a float valve located in a receiving tank with which the conduit is connected (not shown). The catholyte is withdrawn from the exterior of the cathode by conduits leading from the bottom of the chamber formed by the plate 29, the frames 14 and the diaphragms and cathodes.

In operation, the anions are given off on the outer faces of the side bars of the anodes and the ebullition which results causes an upward flow of the electrolyte through the space between the diaphragm and the said outer faces of the anode. This results in a downward flow of the electrolyte through the passageway between the side bars of the anode, a part of the electrolyte passing outward through passageways c between the sections a and b of the side bars. As the electrolyte thus circulates within the anode chamber, entirely around the anode, the more impoverished part thereof passes through the receptacle 50 or in contact with

the salt therein contained, and is resaturated, this action taking place continuously so that the electrolyte is always at practically a point of saturation. The electrolyte percolates through the diaphragm into contact with the cathodes and the cations, which are liberated thereat, are washed down, the liberation of the cations continuing as the catholyte flows down through and on the faces of the cathodes. More or less hydrogen is liberated on the outer faces of the cathodes, and this gas is carried off through conduits 60. The liberation of the hydrogen serves to break up any hypochlorites which are formed on the cathodes and assists in preventing the same from working backward into the anode chamber.

We propose to use as many of the baskets or receptacles 50 as may be necessary although we have shown but one as that is probably sufficient for a cell of the size indicated.

The circulation within the cell of the electrolyte, as herein described, not only keeps the strength of the electrolyte uniform, as the device for holding the salt allows free access of the brine thereto, but at the same time it keeps undissolved salt away from the active parts of the cathode and thus prevents mechanical wear.

Having thus described the nature of our said invention, although without attempting to set forth all of the forms in which it may be made or all of the modes of its use, what we claim is:

1. In an electrolytic cell, a cell body comprising bottom, end and upper side walls, a diaphragm overlapping said walls, a cathode chamber superimposed upon the margin of said diaphragm, a cathode having its marginal edges secured to the cathode chamber to be removable therewith, and an insulating gasket interposed between the cathode chamber and the diaphragm.

2. An anode for an electrolytic cell, comprising horizontally separated plates having an open space between them, each plate being longitudinally divided into vertically separated sections for the circulation of the electrolyte, cross bars connecting said plates and sections thereof, and cathodes adjacent the outer faces of said plates.

3. An anode for an electrolytic cell, comprising separated plates having an open space between them, each plate being longitudinally divided into separate sections, means connecting said plates together and also connecting the sections of each plate, and cathodes adjacent the outer faces of said plates.

4. In an electrolytic cell, a chamber, supports in the cell chamber, and an anode in said chamber resting on said supports so as to be separated from the bottom of said chamber by a free space, said anode com-

prising vertically arranged substantially parallel plates extending longitudinally of said chamber and having their inner faces confronting, and whose upper edges are below the normal level of the electrolyte in 5 the anode chamber for the circulation of the electrolyte.

5. An anode for an electrolytic cell, comprising parallel separated plates, cross bars 10 connecting said plates, and bars or spindles introduced into apertures in said cross bars, and a cathode adjacent the outer face of each of said plates.

6. An anode for an electrolytic cell, comprising parallel separated plates each divided longitudinally into sections, cross bars connecting said plates and said sections, and bars or spindles introduced into apertures in said cross bars, and a cathode adjacent the outer face of each of said plates. 15

7. In an electrolytic cell, a chamber, an anode therein comprising flat plates spaced from the top, bottom and sides of said chamber and having spaced confronting 25 faces to permit a vertical circulation of the electrolyte between and over and under said plates, and a salt receptacle within said chamber and disposed in the path of circulation of said electrolyte for the continuous 30 saturation of the electrolyte.

8. In an electrolytic cell, a chamber, an anode therein comprising parallel flat plates spaced from the top, bottom and sides of said chamber and having spaced confronting 35 faces to permit a vertical circulation of the electrolyte between over and under said plates, and a salt receptacle disposed between said plates in the path of the circulation of the electrolyte.

40 9. In an electrolytic cell, a chamber, an anode therein comprising parallel flat plates spaced from the top, bottom and sides of said chamber and having spaced confronting faces to permit a vertical circulation of the 45 electrolyte between said plates, a cover for said chamber, a tube supported by and depending from said cover, a salt receptacle

below said tube and arranged in the space between the confronting faces of said plates.

10. In an electrolytic cell, a chamber, a 50 cover therefor, a pair of separated parallel flat anode members extending longitudinally of the chamber and spaced from the top, bottom and sides of said chamber, a longitudinally extended salt receptacle, a cover 55 for the chamber, a tube extending through the cover for delivering salt to said receptacle, and a luted cap for closing the upper end of the tube.

11. An electrolytic cell, comprising an 60 open side anode chamber, an anode therein, a diaphragm across the open side of said chamber, and a cathode chamber comprising a frame and outer plate clamped against the margin of said diaphragm, and 65 a cathode having its edges secured to the said frame so that said frame plate and cathode form a removable unit.

12. In an electrolytic cell, a cell body comprising bottom, end and upper side 70 walls, a diaphragm overlapping said walls, a cathode chamber superimposed upon the margin of said diaphragm and a cathode having its edges separated from said diaphragm and secured to the walls of the 75 cathode chamber to be removable therewith as a unit.

13. In an electrolytic cell, a cell body comprising bottom, end and upper side 80 walls, a diaphragm overlapping said side walls, a hollow frame superimposed upon the margin of said diaphragm, a cathode formed of foraminous material having its active face against the active portion of said diaphragm and its edges bent outward 85 to lie inside said frame, and means for securing said edges to said frame.

In testimony whereof we have affixed our signatures, in presence of two witnesses.
